UNITED STATES PATENT OFFICE

147,001

DESIGN FOR AN AUTOMOBILE TOP

Clarkson C. Wormer, III, Detroit, Mich.

Application October 17, 1945, Serial No. 122,926

Term of patent 14 years

(Cl. D14—28)

To all whom it may concern:

Be it known that I, Clarkson C. Wormer, III, a citizen of the United States, residing at Detroit, in the county of Wayne and State of Michigan, have invented a new, original, and ornamental Design for an Automobile Top, of which the following is a specification, reference being had to the accompanying drawings, forming part thereof.

Fig. 1 is a side elevational view of an automobile top showing my new design; and

Fig. 2 is a side perspective view thereof on a somewhat enlarged scale.

The dotted line illustration in the drawing figures is for illustrative purposes only.

A dominant feature of the design is the opaque band extending around the upper edge of the automobile top.

I claim:

The ornamental design for an automobile top, substantially as shown and described.

CLARKSON C. WORMER, III.
